Primary Examiner — Barbara Fox*Assistant Examiner* — Mary C Ramirez(74) *Attorney, Agent, or Firm* — Young & Thompson(57) **CLAIM**

The ornamental design for a lens for television camera, as shown and described.

DESCRIPTION

FIG. 1 is a top, front and left side perspective view of a lens for television camera of my new design;

FIG. 2 is a bottom, front and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a right side elevational view thereof in a manner of use.

The broken lines shown in FIG. 9 depict environmental subject matter and form no part of the claimed design.
